UNITED STATES PATENT OFFICE.

JOSIAH A. WHITMAN, OF CRANSTON, RHODE ISLAND.

PUMP.

SPECIFICATION forming part of Letters Patent No. 268,581, dated December 5, 1882.

Application filed March 28, 1882. (No model.)

To all whom it may concern:

Be it known that I, JOSIAH A. WHITMAN, a citizen of the United States, residing at Cranston, in the county of Providence and State of Rhode Island, have invented certain new and useful Improvements in Pumps; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

The object of this invention is to improve and at the same time cheapen the construction of pumps, and especially the pumps described in Letters Patent to me, dated January 8, 1878, and November 1, 1881; and it consists in the construction of the parts and their combination with other parts, as will be fully hereinafter described.

In the drawings, Figure 1 represents a sectional view of my improved pump. Fig. 2 represents a sectional view of some of the parts enlarged. Fig. 3 represents the lower end of the hollow plunger, having an enlarged bottom end and a contracted part above it. Fig. 4 represents the lower end of the hollow plunger, constructed to receive and secure the valve-box within the contracted part. Fig. 5 represents a modification of Fig. 2; and Fig. 6 represents the lower end of the hollow plunger, with an enlarged lower end to act as a guide without a contracted portion.

A represents the barrel or cylinder of the pump, which may be of cast or wrought metal.

B represents the hollow plunger, preferably made of metal tubing, dressed to be smooth and straight upon its outside, so as to easily reciprocate within a packing-box, and near its lower end it has a contracted part, as at b, and below this is an enlarged or expanded part, b', to be of the diameter to reciprocate freely within the barrel A and act as a guide and a stop to the plunger within the barrel against the lower edge of the packing-box B'. This enlarged part may be constructed by simply turning the metal outward and over against the contracted part b when the valve-box and valve are inserted above or within the contracted part; but when the valve-box b'' is to be inserted from below, and is in

the form seen in Figs. 1 and 4, then the extreme ends of the enlarged part b' will be turned in and underneath the bottom of the valve-box 55 b'' to secure it in place. In either case the enlarged part acts the same to be a guide within the barrel A and a stop to its upward reciprocation against the lower edge of the stuffing box or ring B'. The insertable valve-box and 60 seat b'' may be made of any suitable material—such as cast or wrought metal of any kind or composition, of wood, rubber, vulcanized fiber, or other substance that will not dissolve in water or wear too fast by the friction of the 65 water passing through it, or the action of the valve upon the valve-seat in its function in rising to let the water pass by it, or in falling into its seat to retain the water above it. When this kind of valve-box and a ball-valve are 70 used a transverse pin, c, is or may be inserted over the valve c' to limit its rise in the valve-box. A disk-valve or a valve of any other form may be used in the insertable box.

B' is a metal ring, that forms the lower part 75 of the stuffing-box, which is preferably struck up into form from metal tubing or sheet metal, but may be of cast metal, hard rubber, vulcanized fiber, or other suitable substance in the form seen in Figs. 1 and 2, or in other suitable 80 forms, the upper edge, 1, of which may be larger in diameter than the bore of the barrel of the pump, and at its lower end, 2, it may be contracted, so that its inner diameter of the opening will allow the plunger B to freely slide 85 through it. A transverse crease or groove, 3, is made in the barrel B in its bore, which forms a shoulder at its upper line, and as the ring B' is forced into the top of the barrel, within the bore thereof, the top will contract or spring 90 in until it gets opposite the groove or crease 3, when it is free to expand, when the upper edge, 1, will be within the groove and resting firmly against the shoulder of the groove at its upper line. From this seat it cannot be moved 95 without great force is applied. The same result can be produced by indenting creases in the barrel A, as seen in Fig. 5, as the enlarged upper edge rests firmly against the shoulder of the groove, while the inclination 100 of the groove fits closely the diminishing diameter of the sides of the ring, which prevents the ring from leaving its position and falling down out of the groove. A ring thus con-

structed avoids the usual cast-metal stuffing or packing box to be attached to the outside of the barrel of the pump by screw-threads, as such threads are troublesome and costly to make, while this construction is much cheaper and stronger at the same time. This ring forms only the lower part of the packing-box, while the screw-cap C, which is screwed into the top of the barrel A, and through which the plunger 10 reciprocates, forms the upper part and bears upon any intermediate material for the packing c''. Other means for securing the cap C in or to the barrel of the pump may be used that will be safe, and at the same time become 15 a means to press upon the packing to keep it in proper condition around the plunger and prevent the passage of air or water.

Having thus described my invention, what I claim, and desire to secure by Letters Patent, 20 is—

1. The combination, in a pump, of the barrel A, having transverse grooves or creases 3, with the insertible packing-ring B', constructed in the manner and for the purposes 25 described.

2. The combination, in a pump, of the insertible packing-ring B', groove or crease 3 in barrel A, with the packing c'', and compressing cap C, as and for the purpose described.

3. In a pump such as above described, the combination of the insertible valve-box and valve-seat b'', the hollow plunger B, having a contracted part, b, to receive the valve-box, and an enlarged part, b', to act as a guide and a stop to the plunger, and the packing-ring B' of the barrel A, as and for the purposes described.

4. The insertible valve-box b'', constructed of metal or other suitable material, in combination with a hollow plunger, B, having the contracted part b and the enlarged or expanded part b', as and for the purposes described.

In testimony whereof I affix my signature in presence of two witnesses.

JOSIAH A. WHITMAN.
